(57) **CLAIM**

The ornamental design for a bottle, as shown and described.

DESCRIPTION

FIG. 1 is a front elevational view of a bottle showing my new design;

FIG. 2 is a rear elevational view thereof;

FIG. 3 is a left side elevational view thereof;

FIG. 4 is a right side elevational view thereof; and,

FIG. 5 is a top plan view thereof.

The dash-dash-dash-dash type broken lines shown in the drawing views are included for the purpose of illustrating portions of the design that form no part of the claimed design. The dash-dot-dash-dot type broken lines shown in the drawing views define the boundaries of the claimed design.
